UNITED STATES PATENT OFFICE.

ALBERT H. MORTON, OF LOWELL, MASSACHUSETTS.

SUPPORT AND GUIDE FOR FANCY-ROLLS.

1,118,214.

Specification of Letters Patent. Patented Nov. 24, 1914.

Original application filed February 12, 1910, Serial No. 543,570. Divided and this application filed April 27, 1911. Serial No. 623,774.

To all whom it may concern:

Be it known that I, ALBERT H. MORTON, of Lowell, in the county of Middlesex and the Commonwealth of Massachusetts, have 5 invented certain new and useful Improvements in Supports and Guides for Fancy-Rolls, of which the following description and claims, with the accompanying drawing, is a specification.

10 This application is a division of my application No. 543,570, filed February 12, 1910, for a patent for improvements in carding-engines.

This invention relates to means for supporting-and-guiding the fancy-roll of a carding-engine between its operative and its inoperative positions.

This invention relates to the class of carding-engines in which each engine has a 15 main-cylinder, a doffer, and a fancy, and in which each such part has a casing; the cylinder-casing comprising main-bends or arches and thin sheet-metal covers; the doffer and fancy casings, each comprising 20 shrouds and thin sheet-metal covers; the doffer and fancy covers being fastened to their respective shrouds by screws having heads projecting radially outward from their covers; and, the cylinder and fancy 25 casings being fitted and secured, the one to the other, with corresponding openings therethrough extending across the engine from bend to bend and registering the one with the other. In the engines of this class, 30 it is customary to frequently remove the fancy-casing, containing the fancy, from its operative position, in which it is secured to the cylinder-casing, to an inoperative position where it rests against a stop that is 35 located above the doffer-cover and fastened thereto, and later, to return it to and secure it in its operative position with its opening again registering with the corresponding 40 opening of the cylinder-casing.

45 The invention consists essentially in means extending from near the operative toward the inoperative location of the fancy-cover for supporting-and-guiding the fancy-cover between those locations and in 50 combination therewith of other parts.

In the drawings, which show my invention only in the preferred form: Figure 1 is a side-elevation with the fancy in its operative position. Fig. 2 is an enlarged side-elevation with the fancy-cover touching the

roll-way. Fig. 3 is an end-elevation of the hook engaging the stop. Fig. 4 is a projection of the fancy-stand upon a plane that is radial to and contains the axis of the main-cylinder. Fig. 5 is a sectional-elevation of the fancy journal-bearing and a part of its stand. Fig. 6 is a longitudinal section of the journal-bearing, a fancy-shroud, and a portion of the fancy-cover.

In the preferred form of the invention, 60 the main-cylinder casing 1 supports the fancy-stand 2. The doffer-casing 3 includes the sheet-steel doffer-cover 14. The stop 4 is located above, supported by, and fastened to the doffer-cover. The stand 2 has a support-and-slideway 5 upon which rests or slides the journal-bearing 6 of the fancy. 65 The fancy-casing is numbered 7. The sheet-steel fancy-cover is numbered 15. These 70 parts are as usual.

75 Each one of the two supports-and-guides or roll-ways comprises a steel foundation 8 which conforms in shape to and, when in use, rests upon the top of the doffer-cover near one end thereof. One end of the foundation, when in use, is positioned beneath the operative location of the fancy-cover. The other end of the foundation terminates in the hook 9 for detachably engaging the stop 4 in the hole 10. A soft, frictional, upper face of leather 11 is secured to the foundation to lessen the liability of the slipping of the fancy-cover upon the roll-way. The foundation 8 and its facing 11, taken together, constitute a strip which 80 is especially well adapted for service as a support-and-guide or roll-way. The strip is thicker than any outward radial projections from either cover including such projections of any screw-heads which fasten 85 the doffer and fancy covers to their respective shrouds. This thickness prevents any such projecting parts from colliding with either cover as the fancy-cover rolls upon the strips. If the thickness of the strips 90 was less than the outward radial projection of such parts such collision would occur, the direction of the axis of the fancy would be shifted, the fancy-casing would not roll back to its operative location, 95 its opening would not register with that of the cylinder-casing and the strips would be unsuitable for guides or roll-ways for the fancy. The pair of supports-and-guides or roll-ways, as they are constructed, 100

105

110

are entirely satisfactory as supports-and-guides and as roll-ways. Two strips only are provided for a group of carding-engines. They are transferable from engine 5 to engine throughout the group. When a fancy is to be moved, the pair of strips rests upon the corresponding doffer-cover, one strip near one end and the other strip near the other end thereof. There are two 10 fancy-stands 2 with slide-ways 5 one on each side of the engine. The slideways are so directed relatively to the strips, as is shown in Fig. 2, that the fancy approaches the strips as the bearings 6 6 slide thereupon during the movement of the fancy from the operative position. Each shroud of the fancy-casing has a projecting flange 13. When the operative moves the fancy, he stands in front of the doffer, facing the 15 engine and grasps the flange 13 with one hand and the corresponding flange at the opposite end of the fancy with the other. He then draws the casing forward. The bearings slide upon the stands until the 20 fancy-cover 15 touches the strips, then the fancy-cover rolls upon the strips until it contacts with the stop, as is shown by dotted lines in Fig. 2, and the fancy rests in its inoperative position. The fancy is returned to its stands and its casing is 25 returned to its operative location by a reverse movement and secured therein.

It is not essential to my invention: that the strips should have a metallic foundation and a frictional covering; that the strips should rest upon the doffer-cover; that the strips should be in engagement with, that is, attached to the stop; that the 30

fancy-cover shall roll on the strips, or that the stop shall be located above or fastened 40 to the doffer-cover. It is essential that the fancy shall be supported and guided between its operative and inoperative locations by means extending from near the operative toward the inoperative location 45 of the fancy.

I claim:

1. A carding engine having, in combination, a main cylinder, a fancy therefor, means to support the fancy in operative position, a doffer-cover, means on the doffer-cover to support the fancy in inoperative position and stationary friction strips on the doffer-cover for supporting the fancy while it is being transferred from operative 50 to inoperative position, substantially as described.

2. In a carding-engine having a doffer-cover, a fancy having a cover and a stop for the fancy-cover, the combination therewith of: a pair of strips for roll-ways for the fancy between its operative and inoperative positions, each strip being curved to fit the top of the doffer-cover, having a metallic foundation for location beneath the operative position of the fancy-cover at one end and having a hook for detachable engagement with the stop at the other end, the foundation having a frictional covering for the roll-way.

In testimony whereof, I affix my signature in the presence of two witnesses.

ALBERT H. MORTON.
